(57) **CLAIM**

The ornamental design for martini bottle, as shown and described.

DESCRIPTION

FIG. 1 is a perspective view of a martini bottle design of this invention.

FIG. 2 is a top plan view of the martini bottle of this invention shown in FIG. 1.

FIG. 3 is a bottom plan view of the martini bottle of this invention shown in FIG. 1 shown in FIG. 1.

FIG. 4 is a front elevational view of the martini bottle of this invention shown in FIG. 1.

FIG. 5 is a rear elevational view of the martini bottle of this invention shown in FIG. 1.

FIG. 6 is a left side elevational view of the martini bottle of this invention shown in FIG. 1; and,

FIG. 7 is a right side elevational view of the martini bottle of this invention shown in FIG. 1.
